UNITED STATES PATENT OFFICE.

HENRY R. MYERS, OF FORT THOMAS, KENTUCKY.

DISPLAY ATTACHMENT FOR DOORS.

SPECIFICATION forming part of Letters Patent No. 629,805, dated August 1, 1899.

Application filed October 20, 1897. Serial No. 655,839. (No model.)

To all whom it may concern:

Be it known that I, HENRY R. MYERS, a citizen of the United States, residing at Fort Thomas, in the county of Campbell and State of Kentucky, have invented certain new and useful Improvements in Display Attachments for Doors; and I do hereby declare the following to be a full, clear, and exact description of the invention, reference being had to the annexed drawings, which form a part of this specification.

A certain class of advertising devices to be applied to doors includes swinging members which are prominently displayed as soon as the doors are opened, the exposition of these members being automatically effected by connecting them with cords, chains, or other flexible mediums to the frames or casings of the doors; but these flexible connections, in addition to being complicated and expensive, are liable to stretch by constant use, thereby preventing the prompt action of the swinging members and in some cases rendering them inoperative. To overcome these and other serious objections to the use of cords and chains for the purpose above described, I have devised a display device wherein the swinging member is operated independently of any connection with a door casing or frame, the details of my improved construction being hereinafter more fully described.

In the annexed drawings, Figure 1 shows a preferred form of my attachment applied to a door, the latter being closed and guides of said attachment being sectioned. Fig. 2 is an enlarged horizontal section through the attachment. Figs. 3, 4, 5, and 6 show modifications of the invention.

A represents part of a door casing or jamb, and B is a door hinged to said casing at a, the door being provided with a glass C. Secured to the hanging-stile b of the door is an invertible plate D, which carries all the operative parts of my attachment, the principal members thereof being a right-angled bell-crank, whose levers E E' are preferably made of a single piece of wire and have, respectively, curved heels e e', joined to an eye F, through which is passed a pivot f, that couples said bell-crank to said plate D or other bearing. Furthermore, said plate has at one edge a flange G, pierced at g g'. Again, this plate is slotted at H H' to afford tongues I I', which are so bent as to render their ends parallel with the flange G, as more clearly seen in Fig. 2, the ends of 55 said tongues being perforated, respectively, at i i' and said perforations being in line with the apertures g g' of flange G. By this means two distinct sets of guides are afforded for a reciprocating rigid push-stem J, one end of 60 which is constantly in contact with a lever-heel, while the other end of said stem has a thin head or button j, adapted to occupy the parting between the casing A and door B.

K K' are freely-swinging cards or other display devices or articles so hung from the levers E E' as to normally maintain the perpendicular position shown.

The application and operation of this construction of my attachment are as follows: 70 The plate D of the attachment is first so secured to the hanging-stile b as to insure one edge of the button j being caught between the casing A and door B as soon as the latter is closed, and as the stem J is free to revolve 75 within the guides g' i' it is immaterial which edge of the buttons is thus gripped. Now, owing to the location of pivot f with reference to the guides g' i', the instant the button is caught the opposite end of push-stem J presses 80 against the heel e' of lever E', and thereby maintains the latter in a practically horizontal position. Consequently the other lever

E is about vertical, and any advertisement or other notice displayed on its card K will be 85 visible only to a person within the room to which the door affords access; but the notices on the other card K' can be read both from the outside and inside of the door, provided said card is printed on each side. As soon, 90 however, as the door has been swung open a sufficient distance to release the button j from its confined position the combined weight of lever E' and card K' causes the bell-crank to turn on its pivot f until said lever E' arrives 95 at the vertical position indicated by the dotted line k', at which time the other lever E assumes the horizontal position indicated by the dotted line k. Evidently the positions of the cards are now changed, the card K being exposed at the window and the other card K' concealed by the hanging-stile b. As the lever E swings down its rounded heel e gradually forces back the push-stem J, which is 100

still held in a horizontal position by occupying the two guides $g' i'$. In closing the door the button j contacts with the jamb A and causes the push-stem to advance gradually, and as one end of said stem is always in contact with the bend e' the result of this movement of said stem is to swing the bell-crank on its pivot f , which swinging continues until the door is completely shut, at which moment 5 all the operative parts of the attachment again assume the positions seen in Fig. 1. From this description it is evident my attachment is applied wholly to a door and operates independently of fixtures on the casing or 10 jamb, and for this reason any settling or shrinking either of the door or its casing will not interfere with the proper action of said attachment. Again, as the attachment requires no fixture to the casing, it can be readily 15 applied to a door hung to iron or stone frames, because there is no need of boring or drilling them. Another advantage is due to the fact that the push-stem is quite short and perfectly rigid, and on this account it is not 20 liable to bend and become inoperative when subjected to a thrusting action by the closing of a door, neither will it expand or contract with changes of the weather or constant use, as do cords and other flexible connections 25 used for throwing certain forms of door display attachments.

By providing the plate D with an upper pair of guides $g i$ and the lower pair $g' i'$ said plate can be readily inverted and applied 30 either to a right or left opening door; but in Fig. 3 these guides are omitted and short tubes L L' project from the flange G for the purpose of carrying the stem J, which in this case is shown as being coupled at j' to the heel 35 of e'' of a single pivoted lever E''.

Another modification is seen in Fig. 4, where the push-stem J has a lateral bend j'' , that takes the place of the button j , but a button is preferred for obvious reasons.

45 In another modification (seen in Fig. 5) the bell-crank operates in a reverse manner to the construction represented in Fig. 1, inasmuch as a pulling-spring M retains the lever E''' in a horizontal position while the door is 50 open, but when it is closed the stem J pushes the other lever E''' over to a horizontal position. Consequently the lever E''' now hangs down vertically or practically so.

Finally, the attachment may be applied directly 55 to a door without the intervention of

the plate D; but it is preferred to have a metallic bearing for the bell-crank to turn on, and thereby prevent it marring the hanging-stile b, an equivalent for said plate being seen in Fig. 6, where a single piece of wire is so bent as to afford a pair of coiled guides $i'' i'''$, a pair of bends $d d'$ to receive screws for attaching this wire bearing to a door, and another bend F' to receive the pivot.

I claim as my invention—

1. A display attachment for doors, combining a swinging lever and a rigid reciprocating push-stem, one end of which contacts with a casing or frame when a door is closed, and thereby causes the other end of said stem to 60 thrust against said lever, in the manner described, the attachment being entirely free from connection with said casing or frame.

2. A display attachment, consisting of a plate having a guide, a swinging lever pivoted to said plate, and a push-stem that traverses said guide, and bears against the heel of said lever, said stem being provided with a lateral projection adapted to contact with a casing when the door is closed, as herein described.

3. A display attachment, consisting of an invertible plate having an upper and lower guide, a bell-crank pivoted to said plate, and a push-stem that traverses one of said guides 85 and bears against the heel of one of said levers, said stem being provided with a lateral bearing adapted to contact with a casing when the door is closed, as herein described.

4. For a display attachment to doors, the 90 invertible plate D having a flange G, perforated at g, g' , and integral tongues I, I', having apertures i, i' , in line with said perforations g, g' , all as herein described.

5. A display attachment for doors, combining a swinging lever capable of being pivoted to a door or to a bearing secured thereto, and a rigid reciprocating push-stem having at one end a lateral projection that contacts with a frame or casing when a door is closed and thereby causes the other end of said stem to 100 thrust against said lever, in the manner described, the attachment being entirely free from connection with said frame or casing.

In testimony whereof I affix my signature 105 in presence of two witnesses.

HENRY R. MYERS.
